HARLEY C. MOSLEY, OF PORTSMOUTH, OHIO, ASSIGNOR TO WHITAKER-GLESSNER COMPANY, OF WHEELING, WEST VIRGINIA, A CORPORATION OF WEST VIRGINIA.

CONTROLLING APPARATUS FOR ELECTRIC MOTORS.

1,232,372.

Specification of Letters Patent.

Patented July 3, 1917.

Original application filed March 1, 1915, Serial No. 11,317. Divided and this application filed December 30, 1915. Serial No. 69,360.

To all whom it may concern:

Be it known that I, HARLEY C. MOSLEY, a citizen of the United States of America, and resident of Portsmouth, county of 5 Scio, and State of Ohio, have invented certain new and useful Improvements in Controlling Apparatus for Electric Motors, of which the following is a specification.

This invention relates broadly to a controlling mechanism for electric motors, and it has for its primary object to provide a device whereby electric motors may be automatically rendered operative and inoperative at predetermined related intervals.

15 A further object is to provide, in connection with an electric motor and mechanism which is to be actuated by said motor in a succession of intermittent steps of regular or predetermined length, a system of control 20 whereby said motor is automatically started and stopped at properly timed instants.

For illustrative purposes only the device composing the present invention is herein shown and described in connection with the 25 sheet-cooling apparatus described in my application for Letters Patent filed March 1, 1915, Serial No. 11,317, of which this case is a division.

In describing the invention in detail, reference is herein had to the accompanying 30 drawings, forming a part of this specification, in which—

Figure 1 is a top plan view of the invention applied to the sheet-cooling apparatus 35 mentioned;

Fig. 2 is a section on the line 2—2, Fig. 1;

Fig. 3 is a section on the line 3—3, Fig. 2, showing a face view of the dial switch; and—

40 Fig. 4 is a diagrammatic view of the invention.

Referring to said drawings, 1 indicates, generally, a bull-wheel of an ordinary type employed in galvanizing plants in cooling 45 sheets of metal as they come from the coating bath, said wheel consisting of a shaft 2 having splined thereon a plurality of spaced hubs 3 which carry thereon or have integral therewith disks 4 in the periphery 50 of each of which are rigidly mounted the inner ends of long radially disposed fingers or quills 5, said fingers being located at equidistant intervals in said disks, and the fingers of the various disks being disposed

in radial planes to constitute sheet rests or 55 cradles. Said shaft 2 has its ends suitably journaled on a supporting frame or housing 6 and carries on one end thereof a gear-wheel 7 disposed in operative relation to a worm 8 carried by a worm-shaft 9 journaled 60 on supports 10. Said worm-shaft 9 has fixed thereon a gear 11 in mesh with a pinion 12 carried by a suitably journaled jack-shaft 13 which also carries a gear 14 in mesh with a pinion 15 fixed on the drive-shaft 16 65 of a suitably located motor 17.

Located directly in front of the bull-wheel 1 is a plurality of rollers 18 arranged in parallel horizontal alinement so as to constitute a sheet-receiving table to which sheets are 70 delivered singly as they are advanced from the coating point by means of an endless chain conveyer 19, said conveyer being disposed parallel to the line of the axis of said bull-wheel, and having its delivery end arranged adjacent to said table. Said rollers 18 have their outer ends journaled in a suitable bearing member, as the angle-bar 20, mounted upon a frame 21, and have their inner ends journaled in brackets 22 disposed 75 upon frame members 23, said members and the rollers being separated to afford open spaces 24 through which the fingers 5 may unobstructedly pass as the bull-wheel rotates, as is clearly illustrated in Fig. 1. Each 80 roller 18 carries a bevel gear 25 upon its outer end, said gears being disposed in operative relation to bevel gears 26 carried by a suitably journaled line-shaft 27 which is driven by a constant running motor 28 85 through the intermediacy of a train of speed-reducing gears, as a pinion 29 fixed on the motor drive-shaft 30, which is in mesh with a gear 31 carried by a jack-shaft 32 which also carries a pinion 33 in mesh with a gear 90 34 fixed on said line-shaft.

In practice, the electric circuit to the wheel-driving motor 17 normally remains open, maintaining said motor inoperative. However, each sheet delivered to the sheet-receiving table automatically effects the closing of said electric circuit, setting said motor in operation and actuating said wheel to rotate until said circuit is again opened. The breaking or opening of said circuit is automatically accomplished at predetermined intervals in the rotation of said wheel, said intervals being regulated by the distance 100 105

between adjacent rests or cradles provided on the wheel as aforesaid. The said circuit closing and opening means will now be described, particular reference being had to Fig. 4.

35 indicates a switch-board upon which is located a main-line switch 36 whereby electric current may be conducted, as ordinarily, from main feed wires 37 for supplying a motor circuit and a motor-control circuit. Interposed in the motor-control circuit is a dial switch, designated generally by the numeral 38, comprising a plate 39 of fiber or other suitable non-conductive material mounted adjacent to the end of the worm-shaft 9 and having a pair of concentrically disposed copper ring contacts 40 and 41 formed on the face thereof, one of said contacts, as 41, having a short segment removed therefrom to form an open space 42. Carried by and insulated from said worm-shaft 9 is a copper arm 43 which rests against said ring contacts 40 and 41 and forms a conductor through which current travels between said contacts during the rotation of said worm-shaft, except when said arm is disposed across the open space 42, as shown in Fig. 3, in which position of said arm the motor circuit is broken.

30 Located in the motor control circuit is the shunt coil 44 of a magnetic switch which is generally designated by the numeral 45; also a resistance unit 46, in series with said coil 44 is located in said circuit at a suitable point.

When the apparatus is rendered operative by the closing of the main-line switch 36, the motor control circuit is closed, said circuit comprising a conductor 47 leading from one pole of said main switch to said coil 44, a conductor 48 leading from said coil to ring contact 41, the arm 43, ring contact 40, a conductor 49 leading from said contact 40 to resistance unit 46, and a conductor 50 leading from said resistance unit to the opposite pole of said main switch. The closing of said circuit as aforesaid is not, however, productive of any direct results, due to the fact that the resistance unit 46 offers such resistance to the passage of the current that magnetic switch 45, which is located in the motor circuit is not actuated by its coil 44 to close. When, however, a sheet of metal is delivered to the sheet-receiving table and is carried by the forwardly rotating rollers thereof to its most advanced position, it acts to close a shunt by means of which the resistance unit 46 may be cut out, or short circuited. Said shunt consists of conductors 51 and 52, respectively connected to conductors 48 and 50, and a make-and-break switch, the latter being designated generally by the numeral 53. Said switch 53 is located upon or adjacent to the rear end of the sheet-receiving table in a

position wherein a sheet 59, when deposited on said table and occupying its most advanced position, will accomplish the closing thereof; and it consists of an upright stationary arm 54 bearing an insulated contact 55 and a pivoted arm 56 bearing an insulated contact 57, said contacts 55 and 57 having said conductors 51 and 52, respectively, connected thereto. Said pivoted arm 56 is normally held thrust forward, as by means of a suitably disposed spring 58, in a position wherein its contact 57 is withdrawn from engagement with the contact 55, thus maintaining the shunt open. When a sheet 59, deposited on the sheet-receiving table, as aforesaid, is carried forward on the constantly rotating rollers 18, the foremost edge thereof strikes against the arm 56 of the spring switch 53 and swings said arm rearward against the tension of the spring 58, carrying the contact 57 into engagement with stationary contact 55, closing the shunt circuit and diverting the current from the resistance unit 46. When the current is so diverted, the magnetic switch 45 is immediately closed, the coil 44 of said switch actuating the armature 60 thereof to swing on its pivot 61, carrying a contact 62 mounted thereon into engagement with a contact 63 which is located in the conductor line 47. This action closes the motor circuit through an automatic motor starting device 64 of an ordinary type, a conductor 65 leading from said contact 62 to said starter, a conductor 66 leading from said starter through a series field 67 and commutating pole field 68 to the motor 17, and a conductor 69 leading from said motor and connecting to conductor 50 which, in turn, is connected to one pole of the main line switch 36, as aforesaid.

When the motor 17 starts, actuated by the closing of the motor circuit, the bull-wheel 1 instantly begins to rotate, actuated by said motor through the intermediate gearing hereinbefore described, and the sheet 59 on the receiving table is immediately lifted from said table by the horizontally disposed row of fingers or quills 5 which directly underlie said sheet. When said sheet has been elevated to a point where it no longer interferes with rearward movement of the pivoted arm 56, the latter is instantly actuated by its spring 58 to move rearward, breaking the shunt circuit. Thenceforth the coil 44 is supplied through the dial switch 38 and the resistance unit 46 with sufficient current to maintain the magnetic switch 45 closed, although, as hereinbefore indicated, such current is insufficient in strength to initially close said switch. Once started, the motor 17 continues to run until the arm 43 carried by the worm-shaft 9 rotates to the open space 42 in ring contact 41, whereupon the motor-control circuit

through coil 44 of magnetic switch 45 is broken, resulting in the instantaneous opening of the last mentioned switch and the consequent breaking of the motor circuit.

5 When the magnetic switch 45 is opened, as described, a pivoted contact member 70 of the butterfly type associated with the armature 60 thereof is moved to a position connecting two separated contacts 71 and 72, 10 the former having a conductor 73 interposed between it and the conductor 47, and the latter being connected by a conductor 74 to a similar contact 75 which is connected by means of a butterfly contact 76 to a contact 77 which, in turn, is connected by a conductor 78 to the coil 79 of a magnetic switch 80 similar to the magnetic switch 45. Said coil 79 is connected by a conductor 81 to a contact 82 provided on the armature 83 of 15 said switch 80, and said contact 82 is in turn connected by a conductor 84 to conductor 50. Thus, upon the opening of magnetic switch 45, the magnetic switch 80 is instantly energized and the armature 83 therefore 20 swings forward on its pivot, carrying contact 82 into engagement with a fixed contact 85 which is connected by a conductor 86 to a resistance coil 87 which, in turn, is connected by a conductor 88 to the conductor 66 between the series field 67 and the 25 commutating pole field 68. At the instant that the switch 80 closes, a resistance unit 92 in series with coil 79 and disposed between conductors 74 and 78 cuts in for preventing 30 said coil 79 from receiving such an amount of current as would result in its burning out.

By the closing of the switch 80, as aforesaid, a dynamic brake circuit is established 40 by short-circuiting the armature of motor 17 and the commutating pole field 68 through resistance bank 87, while shunt fields 89, having one side connected by a conductor 90 to the conductor 47 and having 45 its other side connected by a conductor 91 to the conductor 69, are excited by being permanently connected across the line. Thus, immediately upon the motor-control circuit through coil 44 of magnetic switch 50 45 being broken by the passage of the arm 43 to the open space 42 of ring contact 41, as hereinbefore described, a dynamic braking force is exerted which results in the motor being stopped and a resultant stoppage 55 of the bull-wheel. And, as the arm 43 must at all times open the motor-control circuit at the same point in the rotation of the worm-shaft 9, and as the braking effect is precisely the same at each operation, or at 60 each time the braking force is applied, the bull-wheel must at all times stop in proper position, assuming of course that the fingers or quills 5 are properly spaced on said wheel.

65 When the next sheet is deposited upon the

sheet-receiving table, the motor control circuit is closed through the spring-switch 53, and, through the consequent closing of the motor circuit, the motor 17 is again started. The short circuit which includes said spring 70 switch is again broken when the said sheet is lifted from engagement with the arm 57 of said switch, whereupon the motor-control circuit through the dial switch 38 maintains the motor in operation, the arm 43 of the 75 last named switch, in the interval during which spring switch 53 remained closed, having moved from the open space 42 into switch-closing relation to ring contacts 40 and 41. As is apparent, the motor circuit 80 remains closed, actuating the motor 17, until said arm 43 again rotates to said open space 42, whereupon the dynamic brake is again applied in the manner hereinbefore described.

85 As hereinbefore stated, the apparatus herein claimed is shown associated with a rotatable sheet cooling device only for purposes of illustration. As is obvious, this is but a single instance of many uses to which 90 the apparatus is applicable.

What is claimed is—

1. A motor control apparatus, comprising in combination with a motor and main line wires, a normally open motor circuit, and a normally closed control circuit, said control circuit including an electro-magnetic switch for closing the motor circuit, means for maintaining said motor circuit closed for a predetermined period, means for limiting 100 the energization of the electro-magnetic switch to a degree insufficient to close the same but sufficient to maintain the switch closed after once having been closed, and a mechanical switch for cutting out the last 105 mentioned means.

2. A motor control apparatus, comprising in combination with a motor and main line wires, a normally open motor circuit, and a normally closed control circuit, said control circuit including an electro-magnetic switch for closing the motor circuit, means for maintaining said motor circuit closed for a predetermined period, a mechanical switch connected to said control circuit, and means 110 shunted across said control circuit for limiting the energization of the electro-magnetic switch to an inoperative degree prior to the closing of said mechanical switch and for maintaining the magnetic switch closed after 115 it has been operated by the mechanical switch.

3. A motor control apparatus, comprising in combination with a motor and main line wires, a normally open motor circuit, and a normally closed control circuit, said control circuit including an electro-magnetic switch for closing the motor circuit, means for maintaining said motor circuit closed for a predetermined period, a mechanical switch 125

connected to said control circuit, and a resistance for limiting the energization of the electro-magnetic switch to an inoperative degree prior to the closing of said mechanical switch for cutting out said resistance to permit the actuation of said electro-magnetic switch and for holding the latter closed when the mechanical switch is opened.

4. A motor control apparatus, comprising in combination with a motor and main line wires, a normally open motor circuit, a control circuit having a normally closed portion, said closed portion including an electro-magnetic switch for closing the motor circuit, means for maintaining said motor circuit closed for a predetermined period, means for limiting the energization of the electro-magnetic switch, to a degree insufficient to close the same but sufficient to maintain the switch closed after having been so positioned, and a mechanical switch connected to said control circuit and adapted when closed to cut out the last mentioned means.

5. A motor control apparatus, comprising in combination with a motor and main line wires, a normally open motor circuit, and a control circuit, said control circuit including an electro-magnetic switch for closing the motor circuit, means for maintaining said motor circuit closed for a predetermined period, means connected in series with said electro-magnetic switch and said means for maintaining the control circuit closed for limiting the energization of the electro-magnetic switch to a degree insufficient to close the same but sufficient to maintain the switch closed after having been so positioned, and a normally open switch adapted to be mechanically actuated to cut out said means for limiting the energization of the electro-magnetic switch and closing the latter.

6. A motor control apparatus comprising, in combination with a motor and main line wires, a normally open motor circuit, electro-magnetic means for closing said circuit, a normally closed control circuit connected with said means and having a resistance element therein to prevent the energization of the electro-magnetic means to such a degree as is required to initially close the latter and permit of sufficient energization of said means to maintain the latter operative after once having been moved to operative position, and means for moving the electro-magnetic means to operative position.

7. A motor control apparatus comprising, in combination with a motor and main line wires, a normally open motor circuit, a normally closed control circuit, said control circuit including an electro-magnetic switch for closing the motor circuit, means for maintaining said motor circuit closed for a predetermined period, a resistance for normally limiting the energization of the elec-

tro-magnetic switch to an inoperative degree, a mechanical switch for cutting out the last mentioned means, a braking circuit connected across said motor circuit, said braking circuit comprising a short circuit element for the motor armature, and an electro-magnetic switch for closing said braking circuit.

8. A motor control apparatus comprising, in combination with a motor and main line wires, a normally open motor circuit, electro-magnetic means for closing said circuit, a normally closed control circuit connected with said means and having a resistance element therein to prevent the energization of the electro-magnetic means to such a degree as is required to initially close the latter and permit of sufficient energization of said means to maintain the latter operative after once having been moved to operative position, and a normally open shunt circuit in the control circuit adapted to be closed for shunting the resistance and permit of the full energization of said electro-magnetic means.

9. A motor control apparatus comprising, in combination with a motor and an element to be driven thereby, a normally open motor circuit, a normally open magnetic switch in said motor circuit and including an operating coil, a control circuit in which said operating coil is located, means adapted to be actuated for closing said control circuit for energizing said operating coil to close said motor circuit, means maintaining said control circuit closed during a predetermined movement of said element and opening both circuits at a predetermined point in said movement, and dynamic braking means actuated by the opening of the motor circuit for stopping the motor.

10. A motor control apparatus comprising, in combination with a motor and an element to be driven thereby, a normally open motor circuit, a normally open magnetic switch in said motor circuit and including an operating coil, a control circuit in which said operating coil is located, means adapted to be actuated for closing said control circuit for energizing said operating coil to close said motor circuit, means maintaining said control circuit closed during a predetermined movement of said element and opening both circuits at a predetermined point in said movement, and a dynamic brake circuit closed by the opening of the motor circuit.

11. A motor control apparatus comprising, in combination with a motor and an element to be driven thereby, a normally open motor circuit, a normally open magnetic switch in said motor circuit and including an operating coil, a control circuit in which said operating coil is located, means adapted to be actuated for closing

said control circuit for energizing said operating coil to close said motor circuit, means maintaining said control circuit closed during a predetermined movement of 5 said element and opening both circuits at a predetermined point in said movement, a shunt circuit closed by the opening of said motor circuit, said shunt circuit including an energizable element, and a dynamic brake 10 circuit established by the energizing of said energizable element, said brake circuit including a resistance unit and the armature of the motor.

12. A motor control apparatus comprising, in combination with a motor and main line wires, a normally open motor circuit, electro-magnetic means for closing said circuit, a normally closed control circuit connected with said means and having a resistance 20 ane element therein to prevent the energization of the electro-magnetic means to such a degree as is required to initially close the latter and permit of sufficient energization of said means to maintain the latter operative 25 after once having been moved to operative position, and a normally open shunt circuit in the control circuit including a spring-retumed switch adapted to be closed for shunting the resistance to thereby permit 30 of the full current passing to said electro-magnetic means.

13. A motor control apparatus comprising, in combination with a motor and an element to be driven thereby, a normally open motor circuit, a normally open magnetic switch in said motor circuit and including an operating coil, a control circuit in which said operating coil is located, means adapted to be actuated for closing said control circuit for 35 energizing said operating coil to close said motor circuit, a switch in said control circuit adapted to be closed by rotation of the motor and to maintain said control circuit closed during a definite movement of said 40 driven element, a resistance unit associated with the last mentioned switch for maintaining the motor circuit closed after the initial closing of the latter, said switch being automatically opened at a predetermined 45 point in the movement of the driven element for breaking both of said circuits, and dynamic motor-stopping means actuated by the breaking of the motor circuit.

14. A motor control apparatus comprising-

ing, in combination with a motor and an element to be driven thereby, a normally open motor circuit, a normally open magnetic switch in said motor circuit and including an operating coil, a control circuit in which said operating coil is located, 55 spring-retumed means adapted to be actuated to temporarily close the control circuit whereby said operating coil is energized for closing the motor circuit, a switch in said control circuit adapted to be closed promptly 60 upon the motor being started and to maintain said control circuit closed during a definite movement of the driven element, a resistance unit associated with said switch for maintaining the control circuit and the 70 motor circuit closed after the temporary closing means for the former is rendered ineffective, said switch being automatically opened at a predetermined point in said movement of the driven element for breaking 75 both of said circuits, and dynamic motor-stopping means actuated by the breaking of the motor circuit.

15. A motor control apparatus comprising, in combination with a motor and an element to be driven thereby, a normally open motor circuit, a normally open magnetic switch in said motor circuit and including an operating coil, a control circuit in which said operating coil is located, means 80 adapted to be actuated to temporarily close the control circuit whereby said operating coil is energized for closing the motor circuit, a switch having ring contacts located in said control circuit, a rotatable arm 90 driven by the motor and adapted to engage said contacts promptly upon the motor being started, a resistance unit associated with the last mentioned switch and maintaining said coil energized while the switch remains 95 closed, one of said contacts being disengaged by said arm at a predetermined point in the rotation of the latter for breaking both of said circuits, and dynamic motor-stopping means actuated by the breaking of the 100 motor circuit.

In testimony whereof, I affix my signature in presence of two subscribing witnesses.

HARLEY C. MOSLEY.
